TABLE-MAT.

1,127,205.

Specification of Letters Patent

Patented Feb. 2, 1915.

Application filed November 6, 1913. Serial No. 799,589.

To all whom it may concern:

Be it known that we, STANLEY B. DOERNBACH and JAMES HOWARD TAYLOR, both citizens of the United States, residing in the 5 city and county of Philadelphia, State of Pennsylvania, have invented a new and useful Table-Mat, of which the following is a specification.

Our invention consists of a protective 10 pad, mat or blanket adapted to be placed upon the top of a table and beneath the table-cloth, linen mat, or other table napery to protect the polished surface of such table top against the heat from dishes and the 15 effect of liquids which may accidentally be spilled upon the same.

This invention relates to a novel construction of a soft, pliable and noiseless mat or pad which can be made in sections, if desired, and which is employed as a protection 20 of the table top from injury by hot dishes or liquids spilled on the table spread; our novel pad or mat preventing transmission of heat from hot dishes or other heated articles to the surface of the table, 25 which latter is prevented from becoming scratched; our device also preventing moisture from reaching the surface of the table.

It has heretofore been proposed to employ mats composed of interior layers of asbestos covered with flannel or similar material, but when these mats are of a sufficient size to cover the table they become inconvenient by reason of the fact that the 35 asbestos cannot be folded over without breaking it and ultimately destroying the mat, and mats of this character are therefore unhandy and unwieldy if made of the size above suggested. It has also been proposed to make sectional pads and provide the same with hinged devices but mats of this character take up considerable space when not in use, as contradistinguished to our construction, which can be readily 40 rolled up when not in use and placed in a convenient box or drawer occupying but little space out of sight and having no liability of becoming soiled.

By our novel construction wherein we

employ as the bottom member a layer of 50 felt; next a layer of coated fabric with the fabric surface next to the felt and next to which is a thick ventilated flexible woolen pad or the like, against which is a coated fabric with the coated side next to the pad 55 superimposed upon which latter is a washable rubberized top which can be readily cleansed, we have produced a novel device which will effectively protect the surface of the table on which it is placed from 60 being marred, scratched, blistered or otherwise injured by heat or liquids, the pad or mat when not in use being capable of being rolled and placed in a box or drawer out of sight. 65

It further consists of such a protective pad which may be conveniently rolled up when not in use.

It further consists of such a pad which is made in sections to adapt the same to be employed upon extension tables. 70

It further consists of other novel features of construction, all as will be hereinafter fully set forth.

For the purpose of illustrating our invention, we have shown in the accompanying drawing one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of these instrumentalities as herein shown and described. 75

Figure 1 represents a top plan view of our improved pad as adapted to a round table. Fig. 2 represents a top plan view of 90 the pad as adapted to an extension table, two leaves being illustrated as inserted. Fig. 3 represents a sectional view of parts of two sections of the pad at the joint between the same and showing at one end the 95 several plies or layers of fabric separated from each other. Fig. 4 represents a plan view of one of the extension leaves. Fig. 5

represents a transverse section of such leaf. Fig. 6 represents a plan view of a slightly different form of pad.

Similar numerals of reference indicate 5 corresponding parts in the figures.

Referring to the drawings, reference numerals 1 and 2 respectively indicate two main sections of our improved protective pad, and said sections are in the present instance illustrated as semi-circular in outline 10 and placed with their juxtaposed or abutting edges against one another to fit the circular top of a table, but it is evident that the outlines of the pads can be varied to 15 fit table-tops of different shapes and according to the purpose of the pad. The pad is composed of a bottom ply or layer 3 of cloth which may be green billiard-cloth or similar cloth of soft and close texture and 20 having a soft and close nap, so that the cloth can rest softly against a highly finished table-top without danger of scratching or marring it, and has a tendency to be a non-conductor of heat. A ply or layer 4 25 of waterproof coated textile material is placed with its uncoated side against the bottom cloth ply 3.

A cushion ply or layer of woolen ventilated felt, 5, preferably loosely felted, is 30 placed upon the coated side of the waterproof material 4 and another ply or layer, 6, of waterproof material is placed upon the felt-ply 5 with its coated side downward or against the pad 5. A ply or layer, 7, of 35 rubber-coated or impregnated textile tissue, such as the so called "gossamer" from which light waterproof garments are made or its equivalent is placed upon the upper or uncoated side of the waterproof ply 6 and 40 forms a washable surface. The several superposed plies or layers are cut into the desired shape, and are united at their edges by stitches 8 or a suitable binding may be employed, if desired, or tufts may be employed 45 to keep the plies uniform.

When the pad is composed of more than one section, the upper rubber-cloth ply is extended beyond the meeting edge of one section to form a flap, 9, as will be understood 50 from Figs. 1 and 3, which will overlap the meeting edge portion of the other section to protect the joint between the meeting edges of the sections, and the edges of said flaps are preferably overseamed or overcast by stitches, 10, to reinforce such edges.

When the pad-sections are employed for an extension-table, extension-sections or leaves, 11, are employed, as illustrated in Figs. 4 and 5, and are interposed between 55 the edges of the sections to cover the gaps between the same. Said leaves have each a flap, 12, formed by the upper rubber-cloth ply, and having overcast stitches, 13, at its edges, the manner of assembling the parts

being apparent from Fig. 2. Said leaves 11 65 are formed from plies or layers like the other sections.

In the drawings, the pad is illustrated as adapted for a round extension-table, but the pad may be square, oblong, or of any 70 desired form and shaped to fit any form of table and in as many or few sections as required. The pad may also be cut to fit under mats or other table napery.

In Fig. 6 a layer, 14, of fiber-board or 75 similar stiffening material is indicated by dotted lines, which layer will serve to reinforce the outer edges of the pad and render it stiff. The pad will rest with its soft bottom-ply upon the table-top, and will not 80 scratch nor mar the most highly finished surface. The rubber-cloth ply and the waterproof plies will render the pad impermeable to liquid from below and above, and, the felt-ply being protected from above 85 and below by the waterproof plies cannot become wet and be injured by retaining its dampness and forms a pliable ventilated cushion absorbing any moisture created from the hot dishes. The water-proof plies 90 are poor heat-conductors and the inclosed felt-ply and the bottom cloth-ply are likewise poor-heat-conductors, so that no appreciable heat can penetrate the pad from hot articles placed upon the table-cloth to injure the finish of the table-top.

By reason of the overlapping protective flaps, as 9, which we employ, it will be seen that no liquids can flow through the joints of the several parts upon the table, such 100 joints will be durable, and the heated article, as hot plates, soup-tureens or like plates on the table-cloth will not injure the surface of the table or produce white blemishes which will show when the pad or mat is 105 removed, it being evident that when the table is dressed with silk or lace scarfs or covers, such blemishes show through and mar the artistic effect intended by the delicate covering. It will further be apparent 110 that when we employ for the lower pad green baize or similar cloth, as the bottom covering 3, that upon reversing the pad and having the surface 3 uppermost, an efficient and attractive covering for a card 115 table is readily provided.

It will now be apparent that we have devised a novel and useful construction of a table mat which embodies the features of advantage enumerated as desirable in the 120 statement of the invention and the above description, and while we have, in the present instance, shown and described a preferred embodiment thereof which has been found in practice to give satisfactory and reliable 125 results, it is to be understood that the same is susceptible of modification in various particulars without departing from the spirit

or scope of the invention or sacrificing any of its advantages.

Having thus described our invention, what we claim as new and desire to secure 5 by Letters Patent, is:—

A table pad composed of a soft and closely woven cloth-ply, a waterproof ply having its uncoated side against said ply, a felt-ply against the coated side of the waterproof 10 ply, another waterproof ply having its coat-

ed side against the felt-ply, a rubber-coated top-ply having its upper surface washable, and stitches through said plies securing portions of the same together.

STANLEY B. DOERNBACH.
JAMES HOWARD TAYLOR.
